[57] **CLAIM**

The ornamental design for a low profile golf bag stand assembly, as shown and described.

DESCRIPTION

FIG. 1 is a front elevation view of a low profile golf bag stand assembly shown in a retracted position;
 FIG. 2 is an enlarged front elevation view thereof;
 FIG. 3 is a top perspective view thereof;
 FIG. 4 is an enlarged top perspective view thereof;
 FIG. 5 is a side elevation view thereof;
 FIG. 6 is an enlarged side elevation view thereof;
 FIG. 7 is an enlarged top plan view thereof;
 FIG. 8 is a front elevation view thereof in an extended position;
 FIG. 9 is an enlarged front elevation view of FIG. 8;
 FIG. 10 is a top perspective view of FIG. 8;
 FIG. 11 is an enlarged top perspective view of FIG. 8;
 FIG. 12 is a side elevation view of FIG. 8;
 FIG. 13 is an enlarged side elevation view of FIG. 8; and,
 FIG. 14 is an enlarged top view of FIG. 8.
